K. MORSTADT.
CAPSULE CLOSER.

No. 514,842.

Patented Feb. 13, 1894.

UNITED STATES PATENT OFFICE.

KARL MORSTADT, OF PRAGUE, AUSTRIA-HUNGARY, ASSIGNOR TO J. M. GROSVENOR & CO., OF BOSTON, MASSACHUSETTS.

CAPSULE-CLOSER.

SPECIFICATION forming part of Letters Patent No. 514,842, dated February 13, 1894.

Application filed June 19, 1893. Serial No. 478,166. (No model.)

To all whom it may concern:

Be it known that I, KARL MORSTADT, of Prague, Austria-Hungary, have invented certain new and useful Improvements in Apparatus for Locking Medicinal Wafers, of which the following is a specification.

This invention relates to an apparatus for putting up medicines in capsular form, and the object is to provide a practical appliance by which the medicinal articles may be conveniently prepared in large quantities.

The apparatus is particularly designed for closing what are known as "cachets," consisting of concavo-convex wafers of soluble material, provided with flanges by which to unite them. By the use of my apparatus, these cachets may be closed without liability of the powder with which they are filled getting between the edges or flanges.

20 The invention is illustrated in the accompanying drawings, in which—

Figure 1 shows a perspective view of the apparatus, with the cover-plates open and a number of cachets inserted and ready to be closed. Fig. 2 shows a sectional view, with one of the cover-plates closed. Fig. 3 shows a similar section, with the other cover-plate closed. Fig. 4 shows a sectional view, illustrating a way in which supplemental plates 30 may be employed. Fig. 5 shows a plan view of two of these supplemental plates. Fig. 6 shows a top plan view of the apparatus as it appears in closed adjustment. Fig. 7 shows a longitudinal section on line 7—7, of Fig. 6. Fig. 8 shows an end view.

The same letters of reference indicate the same parts in all the figures.

In the drawings, the letter *a* designates a bed-plate, which is supported on legs *a'*, so that it may be elevated above the surface on which it rests. Said bed-plate is provided with a number of concavities *a²* in its upper face, and perforations *a³* are preferably formed in the bases of said cavities for the purpose of allowing the escape of air when the cachets are placed in the cavities. Joint-ears *a⁴* are formed at one side of the bed-plate, and a cover-plate *b* is hinged to said joint-ears, and is provided with a number of openings *b'*, which extend through it and are adapted to register with the concavities *a²* in

the bed-plate *a*, the said cover-plate being adapted to close down and rest evenly upon the said bed-plate. Joint-ears *a⁵* are formed at the opposite side of the bed-plate, and a second cover-plate *c* is hinged to said joint-ears *a⁵*, by means of trunnions *c'*, which engage slots *c²* in the joint-ears. The cover-plate *c* is also formed with a number of openings *c³*, which extend through it and are adapted to register with the cavities in the bed-plate, the said cover-plate being adapted to close down and rest evenly upon the bed-plate.

In the use of the apparatus, the wafers *d*, of which the cachets are composed, are pressed with the fingers into the concavities *a²* in the bed-plate *a*, and into the openings *c³* in the cover-plate *c*, the flanges *d'* of said wafers bearing against the surfaces of the bed-plate and cover-plate respectively. The cover-plate *b* is then closed down upon the bed-plate, and bears upon and completely covers the flanges of the wafers or cachets in the concavities of the bed-plate, as illustrated in Fig. 2. Medicine in powdered or other form is poured into the cachets in the bed plate, and it will be seen that the cover-plate *b* prevents the powder from lodging on the flanges *d'*. Large doses may be introduced into the cachets by means of a funnel, and pressed down with a thimble furnished for the purpose. After the cachets have been filled, the plate *b* is turned back on its hinges, and a dampened roller is passed over the cover-plate *c* so as to moisten the flanges of the cachets therein. The said cover-plate *c* is then closed down upon the bed-plate *a*; a slight pressure will cause the flanges of the cachets to adhere, and then, upon raising the cover-plate *c*, closed cachets will be found adhering thereto, and may be readily removed by inserting the finger through the opening *c³* or by means of a pusher supplied for this purpose. It will be seen that, with an apparatus of this kind, a number of cachets equal to the number of concavities in the bed-plate *a* may be simultaneously closed, and that the apparatus may be very quickly and effectively manipulated.

The concavities in the bed-plate and the openings in the cover-plates may be of vary-

ing sizes; and, to provide for closing cachets of still different sizes, I provide a number of supplemental plates, to be applied on the plate *a* and upon the cover-plate *c*. Two of these supplemental plates *e* and *e'* are hinged together at *e*², and the plate *e* is adapted to be detachably fastened upon the bed-plate *a*, being provided with openings *e*³ corresponding with the concavities in said bed-plate.

The means hereshown for detachably fastening said supplemental plate on the bed-plate consists in lugs *a*⁶, formed on the ears *a*⁵, and under which the said supplemental plate is adapted to engage, said plate being also formed with offsets *a*⁷ to engage the inner sides of the ear *a*⁵ and prevent longitudinal movement of the supplemental plate.

The supplemental plate *e'* is adapted to close down upon the plate *e*, and is provided with openings *e*⁴ adapted to register with the openings in the plate *e*.

A third supplemental plate *f* is detachably fastened to the inner side of the cover-plate *c*, by means of ears *f*' formed on the supplemental plate and engaging slots in the cover-plate, and sliding bolts *f*² in the cover-plate and adapted to engage openings in said ears.

The apparatus, with the supplemental plates attached, is used in the same manner as before described.

When not in use, the supplemental plates *e* and *e'* are carried on the under side of the bed-plate, two of the legs *a*' being provided with notches *a*⁸ which receive the edge of one of the supplemental plates, and the turn-button *g* being fastened in the bed-plate and adapted to engage registering openings *g*' in the supplemental plates.

The complete apparatus is capable of compact adjustment, as illustrated in Figs. 7 and 8, the supplemental plate *f* being carried on the inner side of the cover-plate, and the supplemental plates *e* and *e'* being carried on the under side of the bed-plate, as just described. The slots *c*² in the ears *a*⁵ allow the cover-plate *c* to admit the two plates *b* and *f* between it and the bed-plate.

It is evident the construction here shown may be varied without departing from the spirit and scope of the invention, and therefore the invention is not limited to such construction.

Having thus described my invention, what I claim as new, and desire to secure by Letters Patent, is—

1. An apparatus of the character described, comprising in its construction a bed-plate having one or more concavities, and a cover-plate hinged to said bed-plate and provided with openings adapted to register with the concavities in the bed-plate.

2. An apparatus of the character described, comprising in its construction three leaves or plates hinged together, and provided with registering openings or concavities.

3. An apparatus of the character described, comprising in its construction a bed-plate having one or more concavities, a cover-plate hinged to said bed-plate and provided with openings adapted to register with the concavities in the bed-plate, and supplemental plates hinged together and provided with registering openings, one of the supplemental plates adapted to be detachably fastened on the bed-plate, while the other serves as a cover-plate.

4. An apparatus of the character described, comprising in its construction a bed-plate having one or more concavities, and a pair of cover-plates hinged connected with said bed-plate at opposite sides thereof and provided with openings adapted to register with the concavities in the bed-plate.

5. An apparatus of the character described, comprising in its construction a bed-plate having one or more concavities, a pair of cover-plates hinged to said bed-plate at opposite sides thereof and provided with openings adapted to register with the concavities in the bed-plate, a pair of supplemental plates hinged together and provided with registering openings, one of said plates adapted to be detachably fastened on the bed-plate while the other serves as a cover-plate, and a third supplemental perforated plate adapted to be detachably fastened to one of the cover-plates hinged to the bed-plate.

In testimony that I claim the foregoing as my invention I have signed my name in presence of two subscribing witnesses.

KARL MORSTADT.
